(57) **CLAIM**

The ornamental design for a web camera, as shown and described.

DESCRIPTION

FIG. 1 is a Perspective view of a web camera showing my new design;

FIG. 2 is a front view thereof;

FIG. 3 is a back view thereof;

FIG. 4 is a right-side view thereof;

FIG. 5 is a left-side view thereof;

FIG. 6 is a top view thereof; and,

FIG. 7 is a bottom view thereof.

The broken lines depict portions of the web camera in which the design is embodied that form no part of the claimed design.
